APPARATUS FOR DRYING STRIP MATERIAL

Vincent A. Rayburn, Baltimore, Md., assignor to
 Western Electric Company, Incorporated, New
 York, N. Y., a corporation of New York

Application August 14, 1945, Serial No. 610,831

6 Claims. (Cl. 34—160)

1

This invention relates to apparatus for drying strip material and has for its object the provision of new and improved apparatus for drying strip material.

In the preparation of a vulcanizable compound containing rubber or a rubber-like material for some manufacturing operations, such compound is worked in a mill and is taken from the mill in the form of a long strip which has rough, pebbled surfaces, which often have fissures therein. Sometimes it is desirable to advance such strips through sprays or baths of water to cool them, after which it is necessary to remove the surplus water from them before they are handled or processed further. In the past, it has been attempted to dry the strips by air blasts to blow the water therefrom and by hanging the strips for long periods of time. Both of these methods have been time-consuming and relatively ineffective. The air blasts fail to remove all the water from the rough surfaces and fissures of the strip and hanging the strips requires excessive plant space and is dependent on atmospheric conditions.

One apparatus embodying the invention comprises a pair of hollow rolls having perforations formed in the peripheries thereof. At least one of the rolls is rotated to advance a strip of material positioned between the rolls and means are provided for creating a partial vacuum in hollow portions of the rolls for extracting the water from a wet strip of material positioned therebetween.

A specific embodiment of the invention includes a pair of inrunning hollow rolls having perforations formed in the peripheries thereof. A valve core having a U-section fits into one of the rolls in a position facing the other roll and a second, similar, valve core is positioned in the other roll and is directed toward the first-mentioned roll. When a suction head is applied to the valve cores, moisture from a strip of material being advanced by the inrunning rolls is drawn therefrom by the air being sucked into the valve cores, whereby the strip of material is dried. Compression springs urge one of the rolls toward the other roll so that the strip of material is compressed by the rolls and moisture is squeezed therefrom, which moisture is drawn into the valve cores. Thus, the strip of material is dried and advanced through the apparatus by the rolls.

A complete understanding of the invention may be obtained from the following detailed description of an apparatus forming a specific embodiment

2

ment thereof, when read in conjunction with the accompanying drawings, in which:

Fig. 1 is a top plan view of an apparatus embodying the invention;

Fig. 2 is a vertical section taken along line 2—2 of Fig. 1;

Fig. 3 is a front elevation of the apparatus;

Fig. 4 is an enlarged, vertical, partially sectional view of a portion of the apparatus;

Fig. 5 is a vertical section taken along line 5—5 of Fig. 4;

Fig. 6 is an enlarged, fragmentary vertical section of the apparatus;

Fig. 7 is an enlarged, fragmentary, vertical section taken along line 7—7 of Fig. 6;

Fig. 8 is an enlarged, horizontal section taken along line 8—8 of Fig. 4;

Fig. 9 is an enlarged, fragmentary, vertical section of a portion of the apparatus, and

Fig. 10 is an enlarged, vertical section taken along line 10—10 of Fig. 9.

Referring now in detail to the drawings, an upright frame 20 (Fig. 3) includes a pair of vertical side members 21 and 22, and a tie-cap 23 (Fig. 4), which is secured to the tops of the side members with cap screws 24—24 (Fig. 10). A pair of sleepers 25 and 26 (Fig. 9) are positioned transversely between the members 21 and 22 at the lower extremities of a pair of guideways 27 and 28 (Fig. 10) formed in the upper portions of the webs of the side members 21 and 22. A pair of journal boxes 30 and 31 (Figs. 4 and 9) containing anti-friction liners 32—32 are mounted in the lower portions of the guideways 27 and 28 in axial alignment and are secured to the sleepers 25 and 26, respectively, with cap screws. Shims (not shown) may be installed between the sleepers 25 and 26 and the journal boxes 30 and 31 as required for placing the journal boxes at proper levels. The journal boxes 30 and 31 are provided with guide slots 33—33 (Fig. 8), which receive guide rails 34—34 of the guideways 27 and 28.

A lower roll 35 (Fig. 3) includes a hollow shell 36 (Fig. 4), which has a plurality of sharp approach, short tube, orifices 37—37 formed in the periphery thereof in closely spaced, staggered, longitudinal rows. A pair of tubular end members 39 and 40 (Fig. 9) form journals, which are rotatably fitted in the liners 32—32. A pair of shoulders 41—41 formed on end members 39 and 40 bear against the ends of the journal boxes 30 and 31, and, thus, the roll 35 is laterally confined between the journal boxes. The end members 39 and 40 are secured rigidly to the hollow

shell 36 by set screws 42-42. A gear 43 is keyed to the tubular end 40 at the right of the journal box 31, as viewed in Fig. 9.

The left end, as viewed in Fig. 9, of a cylindrical valve core 46 is keyed to a cap 45 (Fig. 9) bolted to the end of the journal box 30. The core 46 has an elongated open channel 47 (Fig. 6) formed therein, which faces upwardly, as viewed in Fig. 7. The core 46 fits closely within the hollow shell 36, and one end thereof is urged upwardly, as viewed in Fig. 9, by a spring 48 mounted in the cap 45. The other end of the core 46, as viewed in Fig. 4, is supported by a saddle 50, which is urged upwardly by a spring 53 in a yoke 51, which is secured to the side member 22 by rods 52-52 so that the core forms a valve cut-off to confine the passage of air and liquid to a limited portion of the perforated shell. Sharp-edged lips 53 and 54 of the core are so spaced that only a few of the rows of the orifices 37-37 are positioned therebetween.

A pair of journal boxes 55 and 56 (Fig. 9) are provided with a pair of guide slots 51-57 similar to the guide slots 33-33 (Fig. 8) formed in the journal box 31. The journal box 56 is slidably mounted within the guide rails 34-34 above the journal box 31, and the journal box 55 is similarly mounted above the journal box 30. The journal boxes 55 and 56 are urged downwardly, as viewed in Fig. 9, by a pair of compression springs 58-58, which are compressed by a pair of spring-centering seats 60-60 borne by bolts 59-59 adjustably secured by lock nuts 62-62 in tapped bores 61-61 formed in the tie cap 23.

The journal boxes 55 and 56 have secured therein a pair of anti-friction liners 65-65 in which are rotatably mounted a pair of tubular end members 66 and 67 secured to a hollow shell 68 of an upper roll 70. The hollow shell 68 has a plurality of sharp approach, short tube, orifices 71-71 formed in the surface thereof in closely spaced, staggered, longitudinal rows.

A gear 72 (Fig. 4) keyed to the tubular end member 67 of the roll 70 meshes with the gear 43, which is driven by a gear 73 secured on a drive shaft 75, driven by a suitable source of power (not shown). A housing 76 serves to enclose the gears 43, 72 and 73.

A cylindrical valve core 77 is keyed to a cap 80 bolted to an end of the journal box 55. The core 77 is identical with the core 46 and for the sake of simplicity only the core 77 will be described in detail. The core 77 has a pair of annular bearing surfaces 81-81 (Fig. 9) formed exteriorly thereon near the ends thereof, and a substantially annular bearing surface 82 (Fig. 6) is formed on the central portion thereof. Longitudinally extending arcuate bearing surfaces 83-83 (Fig. 7) are formed on the exterior of the upper portion of the core 77.

A pair of arcuate bearing surfaces 86-86 are formed on the exterior of the core 77 adjacent to a plurality of relieved portions 85-85, and an elongated open channel 87 is formed in the core 77. The bearing surfaces 86-86 are immediately adjacent to the channel 87, and the bearing surfaces 81-81, 82-82, 83-83 and 86-86 permit the hollow shell 68 to rotate thereover with a minimum of friction. Sharp-edged lips 78 and 79 of the core 77 are spaced apart a distance so that only a few of the longitudinal rows of the orifices 71-71 are in communication with the cavity 87 at any one time. The cores 46 and 77 are secured in positions in which the channels 47 and 87 are in facing relationship (Fig. 7).

The core 77 has a central dividing web 88 (Fig. 6) formed midway thereof in the channel 87. An arcuate vane or splitter 90 is positioned within the channel 87 near the left end, as viewed in Fig. 6, and a similar arcuate splitter 91 is positioned upwardly and to the right of the splitter 90. A third arcuate splitter 92, which is similar to the splitters 90 and 91, is positioned upwardly and to the right of the splitter 91. A plurality of arcuate splitters (not shown), which are identical with the arcuate splitters 90, 91 and 92, are positioned to the right of the web 88, as viewed in Fig. 6, in a relation symmetrical to that in which the splitters 90, 91 and 92 are positioned.

The web 88 divides the channel 87, and the splitters 90, 91 and 92 serve to even the flow of air through the left portion of the channel 87 when air is drawn from the left end of the channel 87, as viewed in Fig. 6, and the web 88 and the corresponding splitters (not shown) positioned to the right of the web 88 perform a similar function with respect to the right end of the channel 87 when air is evacuated from that portion of the channel.

A stuffing 94 contained in a slot 95 formed in the core 77 between the bearing surfaces 83-83 supplies oil to the interior of the perforated shell 68 from a plurality of bores 96-96 formed in the core 77, which bores are connected with an oil pipe 97 secured in the upper portion of the core 77. Oil is supplied under pressure to the oil pipe 97 by suitable means (not shown).

A plurality of flexible ducts 100-100 (Figs. 2 and 3) are connected to the tubular ends of the cores 46 and 77 and to a header duct 101. The header duct leads to the inlet of a closed eliminator chamber 102, which is provided with eliminator plates 103-103 of a well known type. The outlet of the eliminator chamber 102 is connected to the inlet of an exhaust fan 104 (Fig. 1), which is driven by an electric motor 106 to evacuate the eliminator chamber 102 and form a suction head in the open channels 47 and 87 of the cores 46 and 77. An exhaust pipe 107 serves to convey the air from the fan discharge to a suitable place of disposal.

A drain pipe 108 (Figs. 2 and 3) is connected to the chamber 102 by a pipe 110 and to the bottom of the duct 101 by pipes 111 and 112. The drain pipe 108 carries away any moisture condensed in the duct 101 and any moisture separated from the air stream in the eliminator chamber 102. A suitable trap (not shown) is provided in the drain pipe 108 to provide a water column of sufficient height to counterbalance the suction head of the exhaust fan and seal the eliminator chamber 102 and the header duct 101 from the drain pipe without impeding or retarding the effluent water.

When the fan 104 is driven, air is drawn through the channels 47 and 87 formed in the cores 46 and 77, respectively, and the orifices 37-37 and 71-71 at high velocities, and is drawn at a high velocity over all of the portions of rough, fissured top and bottom surfaces of a wet strip 120, which is composed of plastic material, such as a rubber or rubber-like compound, adjacent to the shells 36 and 68. The shells 36 and 68 squeeze the water out of the fissures in the strip and distort the strip to open the fissures. The air sweeping at a high velocity over these surfaces of the strip draws the moisture from the surfaces and opened fissures of the strip and carries it into and through the orifices 37-37 and 71-71. The air and moisture then are drawn through the channels 47 and 87 and the ducts

100—100 and 101 into the eliminator chamber 102.

In the operation of the apparatus described hereinabove, the lower and the upper rolls 35 and 70 (Fig. 3) are driven in opposite, or in-running, directions by the drive shaft 75, and the motor 106 is energized to drive the exhaust fan 104 (Fig. 1), which exhausts air from the cavities 47 and 87. As the rolls 35 and 70 are rotated the inner surfaces of the shells 36 and 68 are wiped by the stuffing 94, and the stuffing (not shown) corresponding to the stuffing 94, which place coatings of lubricating oil thereon. The lubricating oil assists in forming a substantially air tight seal between the bearing surfaces 86—86 of the core 77 and the inner surface of the shell 68. Thus air is sucked rapidly into the channel 87 through the orifices in the shell 68 adjacent to the channel 87. Any excess oil which may be deposited on the interior surface of the shell 68, together with the air from the exterior of the shell, is sucked therefrom by the suction head in the open channel 87. A seal and lubrication are provided between the shell 36 and the core 46 in a manner identical with that just described and air is sucked into the channel 47 in a manner identical with that just described.

The wet strip 120 of plastic material is inserted between the shells 36 and 68, which are so spaced that they compress the strip of material slightly, and the strip is advanced to the right, as viewed in Fig. 7, by the inrunning action of the shells 36 and 68. As the strip is advanced between the shells, air is sucked into the open channels 47 and 87 at high velocity and is drawn over the surfaces of the strip at a high velocity so that the moisture is drawn from the surfaces and the pores of the strip into the cavities. The moisture-laden air is drawn through the eliminator chamber 102 (Fig. 1), wherein that part of the moisture which remains free is separated from the air as it strikes the eliminator plates 103—103 and drains into the drain pipe 108 (Fig. 2) while the air continues through the chamber 102 and is conveyed away by the exhaust pipe 107. The pressure exerted by the shells 36 and 68 upon the strip 120 also acts to squeeze out any moisture contained in the fissures, pores or folds of the strip.

The springs 48 and 53 (Fig. 9) urge the core 46 upwardly against the shell 36, whereby the bearing surfaces formed on the core 46 adjacent to the entry of the open channel 47, which bearing surfaces correspond to the bearing surfaces 86—86, are maintained in close and sealing relationships with the portions of the interior surface of the shell 36 adjacent thereto. Gravity performs a similar function on the core 77.

The fan 104 creates such a suction head that the velocity of the air sweeping across the portions of the rough, fissured surfaces of the strip 120 adjacent to those of the orifices 37—37 and 71—71 opening into the channels 47 and 87 is very high. The velocity of the air over these portions of the surfaces preferably should be at least 15,000 feet per minute for drawing clear water from the strip, and a velocity of from about 17,000 feet per minute to about 18,000 feet per minute is preferred. Even better results may be obtained by higher velocities but such velocities require a greater suction head than that required to produce the above-mentioned velocities, which are very satisfactory.

The diameters of the shells 36 and 68 are large enough that the orifices 37—37 and 71—71 which

are in communication with the channels 47 and 87, respectively, are always close to the strip, which fact tends to keep the velocity of the air in the vicinity of the open orifices high. The diameters of the shells also are small enough to squeeze out any water in the fissures of the strip without excessively high inter-roll pressures.

The rolls 35 and 70 (Fig. 3) serve the dual function of advancing and squeezing the strip 120, while the moisture on the strip is sucked through the orifices 37—37 and 71—71 formed in the shells. Thus, no separate advancing and extracting means are necessary with the apparatus described hereinabove, which advances strips, such as the strip 120, very efficiently and with economy of space and time.

The above-described apparatus for drying strip material is especially efficacious in drying strips of rubber or rubber-like material. This efficiency is due to the high velocity of the air which is drawn over the surfaces of the strips and the simultaneous squeezing or wringing action on the strip. The strips are dried thoroughly and rapidly by the above-described apparatus.

What is claimed is:

1. Apparatus for drying strips of plastic material, which comprises a frame, a pair of cylindrical shells having a plurality of orifices formed therethrough and mounted on the frame in close parallel relationship, means for rotating the shells in opposite directions to feed therebetween a wet strip of plastic material, means for urging one of the shells toward the other of the shells to compress the strip, a pair of core tubes having channels formed therein, each of which core tubes has a pair of bearing surfaces formed thereon adjacent to the mouths of the channels and is mounted in one of the cylindrical shells with the bearing surfaces thereon in sealing contact with the interior surface of the shell, said core tubes being positioned in the shells with the channels in facing relationship, and means for evacuating the channels to draw air through the orifices in the shells adjacent to the mouths of the channels, whereby any moisture on the surfaces of the wet strip is sucked into the channels.

2. A drying apparatus, which comprises a frame, a pair of cylindrical shells having staggered orifices formed therein and mounted on the frame in close parallel relationship, means for rotating the shells in opposite directions to feed a wet strip of plastic material therebetween, means for urging one of the shells toward the other shell to compress the strip, a pair of core tubes having channels formed therein and also provided with bearing surfaces positioned adjacent to the mouths of the channels, said core tubes being secured in the cylindrical shells with the bearing surfaces thereon in sealing contact with the interior surfaces of the shells and being positioned in the shells with the channels in facing relationship, means for evacuating the channels to draw air through the orifices in the shells adjacent to the mouths of the channels, whereby any moisture on the surfaces of the wet strip is sucked into the channels, and means for creating an air tight seal between the bearing surfaces and the portions of the surfaces of the shells adjacent to the bearing surfaces.

3. A drying apparatus, which comprises a frame, a pair of cylindrical shells having sharp approach, short tube orifices extending through the peripheries thereof and mounted on the frame in parallel relationship, means for urging

one of the shells toward the other shell, means for rotating the shells in opposite directions to advance a wet strip of material therebetween, a pair of cylindrical core tubes having elongated channels formed longitudinally thereof and also provided with bearing surfaces positioned adjacent to the mouths of the channels, said core tubes being positioned in the shells with the mouths of the channels in facing relationship and the bearing surfaces adjacent to the mouths of the channels fitting against the interior surfaces of the shells, said core tubes also being provided with a plurality of annular bearing surfaces which rotatably mount the shells thereon, means for lubricating the bearing surfaces, means for evacuating the channels to draw air rapidly through the orifices in the shells adjacent to the mouths thereof, a pair of dividing webs positioned in the central portions of the channels for dividing the channels, a plurality of vanes spaced in predetermined positions in the cavities for equalizing the flow of air through the channels, and means for urging the core tubes toward each other.

4. Apparatus for drying strips of plastic material, which comprises a frame, a cylindrical shell having orifices formed therethrough and rotatably mounted on the frame, a core having an open channel formed therein and fitted closely within the circular shell, means for applying suction to one end of the channel to cause a rapid flow of air to be drawn into the channel through the orifices in the portions of the shell adjacent to the mouth of the channel, whereby any moisture contained on a strip of material advanced over the shell is drawn into the channel, and a plurality of arcuate vanes positioned in the channel transversely across the channel and facing toward said end of the channel and the mouth of the channel for equalizing the flow of the air through the orifices, the vanes being spaced along the channel.

5. Apparatus for drying strips of plastic material, which comprises a frame, a cylindrical shell having orifices formed therethrough and rotatably mounted on the frame, a core having an open channel formed therein and fitted closely within the circular shell, means for applying suction to one end of the channel to cause a rapid flow of air to be drawn into the channel through the orifices in the portions of the shell adjacent to the mouth of the channel, whereby any moisture contained on a strip of material advanced over the shell is drawn into the channel, and a plurality of arcuate vanes positioned in the channel transversely across the channel and facing

toward said end of the channel and the mouth of the channel for equalizing the flow of the air through the orifices, the vanes being spaced along a line inclined with respect to the mouth of the channel with the vane nearest said end of the channel being nearest to the mouth of the channel and the vane farthest from said end of the channel being farthest from the mouth of the channel.

10 6. A drying apparatus, which comprises a pair of cylindrical shells having orifices extending through the peripheries thereof and mounted in parallel relationship, a pair of cylindrical core tubes having elongated channels formed longitudinally thereof and also provided with bearing surfaces positioned adjacent to the mouths of the channels, said core tubes being positioned in the shells with the mouths of the channels in facing relationship and the bearing surfaces adjacent to the mouths of the channels fitting against the interior surfaces of the shells, said core tubes also being provided with a plurality of annular bearing surfaces which rotatably mount the shells thereon, means for lubricating the bearing surfaces, means for evacuating the channels to draw air rapidly through the orifices in the shells adjacent to the mouths thereof, and means for urging the core tubes toward each other.
